UNITED STATES PATENT OFFICE.

CLARENCE H. HOWARD, OF ST. LOUIS, MISSOURI.

RAILROAD-CAR.

No. 835,528.

Specification of Letters Patent.

Patented Nov. 13, 1906.

Application filed July 20, 1906. Serial No. 327,052.

To all whom it may concern:

Be it known that I, CLARENCE H. HOWARD, a citizen of the United States, residing at St. Louis, in the State of Missouri, have invented 5 a new and useful Improvement in Railroad-Cars, of which the following is a specification.

My invention relates particularly to the dead-block of a railroad freight-car, which is used as a stop for the horn of the coupler 10 when "buffing," and ordinarily consists of a wood block having an iron face-plate or angle-piece and fixed to the end sill and projecting end portions of the draft timbers of the car-underframe.

15 The object of my invention is to provide a rigid and durable metallic structure specially adapted for use as a combined dead-block and connecting piece or brace to the end sill and adjacent butting end portions of the 20 middle longitudinal sills of a car-underframe in those cases where the ordinary draft-timbers are eliminated and the draft-rigging combined directly with the car-body bolster, such as in the arrangement described in the 25 Letters Patent granted to Harry M. Pfleger, October 18, 1904, No. 772,370, for an improvement in draft-gear for railroad-cars, or directly with the said longitudinal sills, as the case may be.

30 The invention consists in features of novelty, as hereinafter described and claimed, reference being had to the accompanying drawings, forming part of this specification, wherein—

35 Figure 1 is a front elevation of my improved combined dead-block and brace as applied to the end sill and longitudinal sills, broken away, of a freight-car underframe in which the ordinary draft-timbers are not 40 used; Fig. 2, a vertical longitudinal section thereof on line 2 2 in Fig. 1 and Fig. 3, a top plan view of the same, the sills being seen in dotted lines.

Like letters and numerals of reference denote 45 note like parts in all the figures.

a a' represent my improved combined dead-block and brace, which is preferably composed of cast-steel integral throughout and may be of any suitable design in configuration and cross-section, such as shown, or 50 otherwise, as desired.

The dead-block proper, a, in the present case is preferably formed with a bottom horizontal projecting portion 1, which is prefer-

ably box-shaped in cross-section and suitably 55 configured on its outer face for engagement by the coupler (not shown) in the usual manner, the rear wall 2 of the bottom portion 1 being extended upward therefrom for a suitable distance and adapted to bear 60 against the outer face of the end sill b of the car-underframe and thence formed with an upwardly-extending offset portion 2', adapted to bear against the sheathing 3 of the car-body, which is inserted thereat between the 65 offset portion 2' and the end sill b, as shown, the block a being secured to the end sill b therethrough by the truss-rod bolts 4 and intermediate bolts 5 or their equivalents, as found most suitable, or, if desired, the rear 70 wall 2 2' of the dead-block a may be level throughout and bear against the sheathing 3 or end sill b, as the case may be.

On the under side of the dead-block a opposite or thereabout to the end of each middle longitudinal sill c of the car-underframe is formed a depending portion 6, which in the present case is an extension of the box-shaped bottom portion 1 of the dead-block a, and from each depending portion 6 projects 80 rearwardly an arm a', which extends beneath and is adapted to bear at the top against the under side of the end sill b and adjacent end portion of the corresponding middle longitudinal sill c, the bearing-face of 85 the arm a' being preferably at right angles, or practically so, to that of the rear wall 2 2' of the dead-block a.

The arm a' may be channel-shaped, as shown, or otherwise in cross-section and is 90 secured to the end sill b and longitudinal sill c, respectively, by the upright bolts 7 7', as shown, or otherwise, as found most suitable.

To the dead-block a on the under side of the depending portions 6 are fixed the end 95 portions of the carry-iron d for the coupler-shank e, Fig. 1, by bolts 8, as shown, or in any other suitable manner.

By this invention the end sill b and middle longitudinal sills c are mutually supported 100 and firmly secured together in every direction by the combined dead-block and brace a a', thereby greatly increasing the strength, rigidity, and durability of the underframe.

What I claim as my invention, and desire 105 to secure by Letters Patent, is—

In a railroad-car, the combination of a metallic dead-block adapted to bear against the

outer face of the end sill, two opposite arms integral with the said block and having an extended bearing longitudinally against the under side of the middle longitudinal sills, 5 and means for fixing the said block and arms to the said sills respectively, substantially as described.

In testimony whereof I have signed my name to this specification in the presence of two subscribing witnesses.

CLARENCE H. HOWARD.
